UNITED STATES PATENT OFFICE.

JOHN ROGERS, OF NEW YORK, N. Y.

DESIGN FOR STATUARY.

Specification forming part of Design No. 7,457, dated May 26, 1874; application filed May 16, 1874.

[Term of Patent 14 years.]

To all whom it may concern:

Be it known that I, JOHN ROGERS, of New York city, New York, have invented a Design for a Piece of Statuary, of which the following is a specification:

The nature of my design is fully represented in the accompanying photographic illustrations.

The design is called "Hide and Seek—Whoop!"—and represents a little girl hiding behind a vase resting on top of the trunk of a tree. With her right hand she is drawing her skirts more out of view, while she plays with the beads of her necklace with her left. The handles of the vase are made by squirrels sitting on twigs eating nuts, while the sides of the vase are ornamented with oak leaves.

What I claim as my invention is—

The design for a piece of statuary, as described and shown.

JOHN ROGERS.
